2 SHEETS-SHEET 2.

UNITED STATES PATENT OFFICE.

JOHN LALLY, OF BOSTON, MASSACHUSETTS.

COLUMN CAP OR BASE.

1,071,523.

Specification of Letters Patent. Patented Aug. 26, 1913.

Application filed July 9, 1912. Serial No. 708,453.

To all whom it may concern:

Be it known that I, JOHN LALLY, a citizen of the United States, residing at Boston, in the county of Suffolk and State of Massachusetts, have invented certain new and useful Improvements in Column Caps or Bases, of which the following is a specification, reference being had therein to the accompanying drawing.

10 This invention relates to column caps, the object in view being to provide a cap or connection for columns and the several sections thereof, especially designed for fire-proof construction, provision being made 15 whereby the columns may be built up to any desired height and adapted to support the beams and rafters at the proper elevations.

With the above and other objects in view, 20 the nature of which will more fully appear as the description proceeds, the invention consists in the novel construction, combination and arrangement of parts as herein fully described, illustrated and claimed.

25 In the accompanying drawings:—Figure 1 is a vertical section through a column cap embodying this invention, showing the same combined with a column casing or section. Fig. 2 is a similar view with the lower flange 30 omitted. Fig. 3 is a similar view showing a cap or sectional construction. Fig. 4 is a top plan view of the upper or crown member of the sectional cap. Fig. 5 is a detail view of one-half of the body of the 35 sectional cap. Fig. 6 is a vertical section through a double cap, showing the manner of connecting adjoining column sections. Fig. 7 is a similar view showing the use of two column caps to form a double cap. 40 Fig. 8 is a similar view showing a double cap of sectional construction. Fig. 9 is a detail sectional view of a hollow or tubular anchor.

45 Referring to the drawings 1 designates the body of the cap, or, as it may be termed the lower cap member, while 2 designates the upper or crown member of the cap, and it will be noted the upper and lower members of the caps, both, have overlapping 50 and interfitting hollow or recessed bosses, the recessed portion of the body 1 being externally screw-threaded and the recess portion of the crown member being internally screw-threaded to fit over the 55 threaded portion of the body, whereby the crown member 2 is adapted to be adjusted

up and down on the body by turning or revolving the crown member, for the purpose of setting the beam or rafter supporting surface of the crown member at the 60 desired elevation, 3 representing such supporting surface. The crown member 2 may be provided with diametrical projections 4 with which a suitable implement may be engaged wherewith to turn said member 65 and obtain the required adjustment.

The construction above described is shown in Fig. 1, wherein it will also be seen that the body 1 is provided with a downwardly extending annular flange 5 which enters the upper portion of the lower column section or casing 6. Under the preferred embodiment of this invention the flange 5 has an external diameter sufficiently less than the internal diameter of the casing 6 to allow the filling of the casing and cap to enter and fill the annular space between said parts to assist in securing the cap to the column casing and making a solid column as a whole. The body 1 is also provided with an annular shoulder or seat 7 which rests directly upon the top edge of the next lower column section or casing and in this way the threaded adjustment between the upper and lower cap sections or 80 members is obtained without in the least weakening the cap or the column casing. The body 1 is held from turning relatively to the casing 6 by means of a fastener, such as a bolt or rivet 8 passing through the 85 flange 5 and the casing 6.

To securely fasten the cap to the casing, I employ an anchor 9, one end of which passes through a hole in an anchor plate 10 extending across the inside of the body 1 and rigidly connected therewith, the other end of the anchor extending well down into the filling of the casing and having an enlargement or head 11 which is embedded in the filling. The upper end of the bolt or anchor 100 9 may be secured to the anchor plate 10 by means of a nut 12. It will be understood that the body of the cap is associated with the column casing before the filling is placed in position. The filling is put in in a 105 plastic condition and hardens around the anchor 9, flange 5, and anchor plate 10, thus securely binding the cap to the casing. The crown member 2 may then be adjusted to suit.

If desired the flange 5 may be dispensed with as shown in Fig. 2, or a short flange

13 may be substituted therefor, and in lieu of the anchor shown in Fig. 1 a tubular anchor 14 may be used as shown in Figs. 2 and 9, the same consisting of a suitable length of pipe one end of which is flared or swaged out as shown at 15 to fit into a hole of corresponding shape and size in the anchor plate. At the other end the anchor 14 may have a detachable head 16 threaded thereon like an ordinary nut.

To form a double cap or as it may be termed a combined cap and base, two caps such as is shown in Fig. 1, may be placed together in reversed position as shown in Fig. 7 and bolted together through the crown plates as shown at 17.

The cap may be of sectional construction as shown in Figs. 3, 4 and 5, in which it will be observed that the crown plate is made separate from the brackets 18. To this end the internally threaded part of the crown member is divided diametrically into two equal sections and said sections are provided with lateral flanges 19 which underlie the plate and are fastened thereto as shown at 20, the said flanges 19 abutting on the line of division of the bracket sections, as shown in Fig. 4. In like manner the body 1 may be composed of twin sections each in the form of a hollow half cylinder, as shown in Fig. 5, said sections, when fitted into the casing, being firmly held thereby. The bracket sections 18 will ordinarily be provided with holes to receive connecting bolts 21.

If desired, a double cap, or a combined cap and base, may be formed by providing the crown plate with both upwardly and downwardly extending internally threaded bosses, as shown in Fig. 6, and these bosses may be of different sizes, as shown in the same figure, to enable column sections or casings of different sizes to be connected up.

Fig. 6 shows beams 22, resting on the crown plate of the combined cap and base. These beams may be secured by screws or bolts 23 passing through the crown plate into the beams, or said beams may be fastened together and at the same time to the column, by means of semicircular tie-straps 24, two of which are employed at each joint, each passing half way around the column while the ends of the straps are extended laterally to rest against opposite sides of the beams to which they are securely fastened by bolts 25 passing through the beams.

Another way of making up a double cap, or a combined cap and base is shown in Fig. 8 in which a single crown plate is employed, with sectional brackets 18 secured to the upper and lower sides thereof by bolts 26 or their equivalent.

Under each and all of the arrangements shown and described, it will be seen that a screw thread adjustment is provided for whereby the supporting surface for the beams or rafters may be accurately fixed; also that the said adjustment is provided for without in the least impairing the strength of the parts of the column.

I claim:—

1. The combination of a casing, an inner section of a cap having one end extending into the casing and the outer end threaded, there being a peripheral shoulder intermediate the ends of said section and engaging the casing, and an outer section threaded on the inner section and including a crown plate.

2. The combination of a casing, an inner section of a cap having one end extending into the casing and the outer end threaded, there being a peripheral shoulder intermediate the ends of said section and engaging the casing, an outer section threaded on the inner section and including a crown plate, a plate arranged within the inner section, concrete in the cap and casing, and an anchoring device embedded in the concrete of the casing and connected with the plate within the cap.

3. The combination of a casing, a concrete filling in the casing, an inner section of a cap having a portion extending into the casing and embedded in the concrete, the outside of the upper portion of the inner cap section being threaded, said inner section having means between its ends to seat on the end of the casing, and an outer section having a threaded engagement with the inner section and including a crown plate.

4. A column structure including alining column casings, an inner cap section for each casing extending into the latter and having an outer threaded end, and an outer section having separate threaded portions for engaging respectively the threaded ends of the inner sections.

5. A column structure including alining column casings, an inner cap section for each casing extending into the latter and having an outer threaded end, and an outer section having separate threaded portions for engaging respectively the threaded ends of the inner sections, there being a crown plate between the two threaded portions of the outer section.

In testimony whereof I affix my signature in presence of two witnesses.

JOHN LALLY.
